SHOE

Dominick B. Caratozzolo, Bronx, N. Y.

Application February 14, 1945, Serial No. 577,738

5 Claims. (Cl. 36—22)

1

This invention relates to sole constructions for shoes.

More particularly, the invention contemplates a new and improved sole construction which is characterized by an outer sole having a substantially U-shaped marginal recess extending around the toe portion and along two sides to the back of the heel. It is proposed to use a substantially U-shaped recess of the outer sole for engaging over and clamping the edges of the shoe upper in position.

The invention also contemplates the use of a shank piece having a half-moon shaped front end fitted on the raised portion of the outer sole and extending from the shank area to the back of the heel. Furthermore, a top shank piece is fitted around the back portion of said marginal strip from the shank area to the back of the heel.

The invention also contemplates the use of a sole cover piece engaged across the front portion of the marginal strip from the toe area to the shank area.

Still further the invention proposes the construction of a sole as briefly explained, which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a plan view of a new sole construction for shoes in accordance with this invention.

Fig. 2 is an enlarged vertical sectional view taken on the line 2—2 of Fig. 1.

Fig. 3 is a perspective view of the sole with various pieces separated so that each may be individually seen.

The sole construction for shoes, in accordance with this invention, includes an outer sole 10 having a substantially U-shaped marginal recess 11 extended around the toe portion and along the two sides to the back of the heel. A shank piece 12 having a half-moon shaped front end is fitted upon the raised central portion 13 of the outer sole 10 and extends from the shank area to the back of the heel.

A substantially U-shaped marginal strip 14 is fitted around the U-shaped recess 11 of said outer sole 10. A top shank piece 15 is fitted around the back portion of the marginal strip 14 and extends from the shank area to the back of the

heel. A front cover piece 16 is engaged across the front portion of the marginal strip 14 from the toe area to the shank area.

A small space 17 exists between the marginal strip 14 and the face of the recess 11 of the outer sole 10 into which the edge portions of the shoe upper may be engaged. The parts are secured together in accordance with similar standard shoe construction as now practiced.

This arrangement includes a half-moon shaped tip 20 formed with the score lines 21 in the marginal recess 11 of the shoe to facilitate flexing of the shoe.

The dominating feature of the invention resides in the fact that the marginal recess 11 of the outer sole is U-shape. With this arrangement the raised portion 13 extends completely to the back of the heel. Another feature of the invention resides in the fact that the marginal strip 14 is similarly of U-shape.

A still further improved arrangement of the sole resides in the provision of the two shank pieces, namely, the shank piece 12 and the top shank piece 15. The shank piece 12 serves to thicken the back portion of the raised section 13 of the outer sole 10. The top shank piece 15 engages over the rear half of the marginal strip 14 and the shank piece 12. The front cover base 16 is used to cover the junction of the marginal strip 14 and the raised portion 13.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A sole construction for shoes, comprising an outer sole having a substantially U-shaped marginal recess extending around the toe portion and along the two sides to the back of the heel, a shank piece having a half-moon shaped front edge fitted upon the raised portion of said outer sole and extending from the shank area to the back of the heel, a substantially U-shaped marginal strip fitted around said U-shaped recess of said outer sole, a top shank piece fitted around the back portion of said marginal strip from the shank area to the back of the heel, and a front cover piece engaged across the front portion of said marginal strip from the toe area to the shank area.

2. A sole construction for shoes, comprising an outer sole having a substantially U-shaped marginal recess extending around the toe portion and along the two sides to the back of the heel, a shank piece having a half-moon shaped front edge fitted upon the raised portion of said outer sole and extending from the shank area to the back of the heel, a substantially U-shaped marginal strip fitted around said U-shaped recess of said outer sole, a top shank piece fitted around the back portion of said marginal strip from the shank area to the back of the heel, and a front cover piece engaged across the front portion of said marginal strip from the toe area to the shank area, said outer sole having a raised portion defined by said marginal recess.

3. A sole construction for shoes, comprising an outer sole having a substantially U-shaped marginal recess extending around the toe portion and along the two sides to the back of the heel, a shank piece having a half-moon shaped front edge fitted upon the raised portion of said outer sole and extending from the shank area to the back of the heel, a substantially U-shaped marginal strip fitted around said U-shaped recess of said outer sole, a top shank piece fitted around the back portion of said marginal strip from the shank area to the back of the heel, and a front cover piece engaged across the front portion of said marginal strip from the toe area to the shank area, said top shank piece being engaged across the back section of said marginal strip and top face of said half moon shaped shank piece.

4. A sole construction for shoes, comprising an

outer sole having a substantially U-shaped marginal recess extending around the toe portion and along the two sides to the back of the heel, a shank piece having a half-moon shaped front edge fitted upon the raised portion of said outer sole and extending from the shank area to the back of the heel, a substantially U-shaped marginal strip fitted around said U-shaped recess of said outer sole, a top shank piece fitted around the back portion of said marginal strip from the shank area to the back of the heel, and a front cover piece engaged across the front portion of said marginal strip from the toe area to the shank area, said front cover piece serving to cover the adjacent edges of said raised portion and said marginal strip.

5. A sole construction for shoes, comprising an outer sole having a substantially U-shaped marginal recess extending around the toe portion and along the two sides to the back of the heel, a shank piece having a half-moon shaped front edge fitted upon the raised portion of said outer sole and extending from the shank area to the back of the heel, a substantially U-shaped marginal strip fitted around said U-shaped recess of said outer sole, a top shank piece fitted around the back portion of said marginal strip from the shank area to the back of the heel, and a front cover piece engaged across the front portion of said marginal strip from the toe area to the shank area, said front cover piece having a rear tip which engages over the front edge of said top shank piece.

DOMINICK B. CARATOZZOLO.
